UNITED STATES PATENT OFFICE.

HIRAM J. YOUNG, OF SYRACUSE, NEW YORK, ASSIGNOR TO THE O. M. EDWARDS COMPANY, INC., OF SYRACUSE, NEW YORK, A CORPORATION OF NEW YORK.

LOCK.

1,407,312.

Specification of Letters Patent. Patented Feb. 21, 1922.

Application filed January 8, 1919. Serial No. 270,117.

To all whom it may concern:

Be it known that I, HIRAM J. YOUNG, a citizen of the United States, and a resident of Syracuse, in the county of Onondaga and 5 State of New York, have invented a certain new and useful Lock, of which the following is a specification.

This invention has for its object a lock mechanism especially applicable for padlocks which is particularly simple in construction, economical in manufacture and highly efficient and durable in use; and the invention consists in the novel features and in the combinations and constructions here- 10 inafter set forth and claimed.

In describing this invention reference is had to the accompanying drawings in which like characters designate corresponding parts in all the views.

20 Figure 1 is an elevation of a padlock embodying one form of my invention, the front section of the casing being removed and the lock mechanism being shown in its operative position.

25 Figure 2 is a view similar to Fig. 1 showing the position of the lock mechanism after the shackle is opened.

Figure 3 is a view similar to Figure 1 showing the lock mechanism in an intermediate position occupied just after the shackle is released and before it springs to its open position.

Figure 4 is a detail view of one of the tumblers.

35 Figure 5 is a sectional view partly in elevation, taken on line 5—5, Fig. 1.

This lock comprises generally, a casing, a locking member as a shackle and lock mechanism mounted in the casing and co- 40 acting with the shackle to open the same after the locking mechanism has been operated far enough to release the shackle.

1 designates the casing which may be of any suitable form, size and construction, it 45 being preferably composed of base and front sections 2, 2^a, which are held together by posts 3, 4, 5, 6 and 7 rising from the base section and which have reduced portions for entering corresponding holes in the top section 2^a, these reduced portions having their heads riveted or spread to form shoulders which prevent the removal of the front section 2^a.

8 designates the shackle which is pivoted 50 at one end on the post 7 and has its other

end movable through a suitable opening 9 in the casing to cooperate with the lock mechanism.

10 designates the tumblers of the lock mechanism. There may be any number of 60 tumblers and in this embodiment of my invention I have shown two. The tumblers are spring pressed and are provided with means coacting with the shackle to open the shackle after the tumblers have been moved 65 by the key against the action of the spring far enough to release the shackle. Each tumbler as here shown is slidably mounted in the casing and also has a slight pivotal movement to open the shackle after the 70 tumbler has been moved rectilinearly far enough to release the free end of the shackle. As here shown, the tumbler includes a body, 11 having a bearing as a slot or notch 12 on the post 4, said post engaging the lower 75 edge 13 of the body during the sliding movement of the body. The body also has an upper surface 14 coacting with the lower edge surface 15 of the pivoted end of the shackle 8 so that the post 4 and lower edge 80 face 15 guides the tumbler during its rectilinear movement. A spring 16 presses and holds the tumblers in their operative engagement with the shackle and also moves the shackle pivotally about the post 4 to 85 open the shackle after being released from the tumblers.

The tumbler is formed with an upwardly extending part 17 here shown as in the form of a hook for interlocking with the notched 90 or hook shaped end 18 at the free end of the shackle, and the tumbler is also shown as formed with a depending arm 19 extending downwardly from the body for engaging the bit of the key. The parts 17, 18 are provided 95 with curved faces 17^a, 18^a which permit the shackle to latch into engagement with the tumblers.

The surface 15 at the pivoted end of the shackle, has a cam or backed off portion 20 which permits the tumblers to have a forward pivotal movement after the shackle has been released so that the ends of the hook shaped parts 17 of the tumblers close the opening 9 when the lock is unlocked and 100 also the shackle has a seat or notch 21 at the end of the cam surface 20 for receiving a tooth or corner 22 on the tumbler whereby after the tumbler has been moved far enough to release the free end of the shackle, 105 110

the tooth 22 enters the notch 21 and causes the pivotal movement of the tumbler under the reaction of the spring to be transferred to the shackle and open the shackle.

5. 23 is a ward, here shown as having a base plate 24 mounted between the posts 4, 5 and held in position by said posts.

The spring 16, as here shown is a coiled spring encircling the post 6 and has arms 10 25, 26 at its opposite ends, one of which as 25 presses against the casing and the other 26 against the tumblers.

The tumblers may be pressed from sheet metal and in order to space the same apart, 15 are provided with marginal flanges 27 the edges of which rest either upon the inner face of the base plate 2 or on the upper face of the adjacent tumbler.

In assembling the lock, the shackle 8 is 20 placed upon the post 7, the ward 23 between posts 4, 5, the spring 16 on the post 6, and the tumblers on the post 4.

In operation, during the unlocking of the lock, the bit of the key engages the portions 25 19 of the tumblers and causes the tumblers to move rectilinearly to the right, the tumblers being guided in their movement on the post 4 and on the surface 15.

When the hook shaped part 17 of the tumblers moves out of interlocking engagement 30 with the free end of the shackle 8, the spring 16 presses upwardly on the right hand end of the bodies of the tumblers causing the tumblers to press on the surface 20 and seat 35 21 on the shackle and throw the shackle into its open position, the tumblers during this movement moving into the position shown in Figure 2. During closing of the shackle the cam surface part 20 slightly moves the 40 tumblers pivotally in a retrograde direction so that the curved surface 18^a on the shackle can engage the curved surfaces 17^a on the tumbler and cause the shackle to latch into interlocking engagement with the tumbler.

45. What I claim is:

1. A lock comprising a casing, a shackle and lock mechanism located within the casing comprising a shiftable tumbler comprising a single member having a part rigid 50 therewith, means coacting with the shackle to move the same into its open position when the lock mechanism has been operated to shift the tumbler and release the shackle, substantially as and for the purpose described.

2. A lock comprising a casing, a shackle and lock mechanism within the casing comprising a shiftable tumbler, the tumbler comprising a single member having a part rigid 60 therewith, and means coacting with the shackle to move the same into its open position when the lock mechanism has been operated to shift the tumbler on its pivot to release the shackle, substantially as and for 65 the purpose specified.

3. A lock comprising a casing a shackle pivoted at one end to the casing, a tumbler mounted to move pivotally and rectilinearly in the casing, the tumbler being movable into and out of interlocking engagement 70 with the free end of the shackle during its rectilinear movement and having means coacting with the pivoted end of the shackle during the pivotal movement of said tumbler to move the shackle on its pivot, and a spring 75 acting on the tumbler tending to press the same to its locked position, substantially as and for the purpose specified.

4. A lock comprising a casing, a shackle pivoted at one end to the casing, a post 80 located in the casing, a tumbler mounted on the post and slidably crosswise thereof and also having a pivotal movement relatively thereto, the shackle having a seat on the edge of its pivoted end and the tumbler having an arm engaging said seat, and a spring 85 acting on the tumbler tending to press the same to its locked position and to move the tumbler about its pivotal axis and press said arm against said seat, substantially as and 90 for the purpose described.

5. A lock comprising a casing, a shackle pivoted at one end to the casing and having 95 its other end movable into and out of the casing and a tumbler mounted in the casing and including a body having an arm coacting with the lower edge face at the pivoted end of the shackle, a guide located in the casing and engaging the body at a point remote from the pivoted end of the shackle, the tumbler being movable rectilinearly and also pivotally relatively to the guide and having a part extending upwardly from the body for interlocking with the free end of the shackle, and a key engaging arm extending 100 downwardly from the body, substantially as and for the purpose set forth.

6. A lock comprising a casing, a shackle pivoted at one end to the casing and having 110 its free end movable into and out of the casing, the shackle having a cam surface at its pivoted end, a tumbler mounted in the casing and including the body having an arm coacting with the cam face at the pivoted 115 end of the shackle, a guide located in the casing and engaging the body at a point remote from the pivoted end of the shackle, the tumbler being movable rectilinearly and also pivotally relatively to the guide and having a part extending upwardly from the body 120 for interlocking with the free end of the shackle, and a key engaging arm extending downwardly from the body, and a spring acting on the tumbler and tending to press the same toward its locked position and 125 move the same about its pivotal axis, substantially as and for the purpose described.

7. A lock comprising a casing, a shackle pivoted at one end to the casing and having 130 its other end movable into and out of the

casing, the pivoted end of the shackle being provided with a cam portion, a tumbler pivotally and slidably mounted in the casing and having an arm engaging said cam portion at the pivoted end of the shackle and also having a part for interlocking with the free end of the shackle and a key engaging part, and a spring acting on the tumbler, substantially as and for the purpose specified.

8. A lock comprising a casing, a shackle pivoted at one end to the casing and having its other end movable into and out of the casing, the pivoted end being provided with a cam portion and a seat at one end of the cam portion, a tumbler pivotally and slidably mounted in the casing and having an arm slidably engaging said cam portion at the pivoted end of the shackle and a tooth 20 for engaging said seat, the tumbler also having a part for interlocking with the free end of the shackle, and a key engaging part, and a spring acting on the tumbler and tending to move the same to its locked position, 25 substantially as and for the purpose set forth.

9. A lock comprising a casing having a post therein, a shackle pivoted at one end to the casing and having its other end movable into the casing, the shackle having a cam 30 surface on the lower edge of its pivoted end, and a seat at the end of the cam surface, a tumbler mounted on the post and movable crosswise thereof and also pivotally movable about the post, the tumbler having an 35 upper surface engaging said cam surface at the pivoted end of the shackle, and a shoulder for engaging said seat, and also having a part arranged to interlock with the free end of the shackle and a key engaging part, and 40 a spring acting to resist movement of the tumbler and to press the same against said cam surface and move the tumbler on its pivot after the tumbler has been moved far enough to release the free end of the shackle, 45 substantially as and for the purpose described.

In testimony whereof, I have hereunto signed my name, at Syracuse, in the county of Onondaga, and State of New York, this 50 21st day of December, 1918.

HIRAM J. YOUNG.
